UNITED STATES PATENT OFFICE

PER GUNNAR PALMGREN, OF GOTTFENBORG, SWEDEN, ASSIGNOR TO AKTIEBOLAGET SVENSKA KULLAGERFABRIKEN, OF GOTTFENBORG, SWEDEN, A CORPORATION OF SWEDEN

ROLLING MILL GUIDE

Application filed October 17, 1929, Serial No. 400,207, and in Sweden October 23, 1928.

In many cases it is usual to provide a guide before the rolls in rolling mills in order to guide the material to the pass and to prevent it from twisting in the pass.

- 5 When material with oval section enters a round pass, it is necessary for the guide to fit snugly about the material in order to give satisfactory results. This makes it more difficult for the material to enter the guide, 10 and automatic entering is impossible, unless the guide is opened sufficiently to allow the material easy access. If material of oval section is to be rolled in a square pass, the 15 guidance will be very unsatisfactory and the shape of the material after passing through the mill will not be that desired. The above disadvantages are to be found in looping mills in which the stands are placed side by side as well as in continuous mills 20 in which the stands are placed one after the other.

In other cases, for example, when a square section is to enter an oval pass, the chief function of the guide is to guide the material 25 in a lateral direction so that it enters the pass symmetrically. If the guide is too loose, the material in most cases does not enter the pass in the centre and consequently fills the pass unequally.

- 30 When the material is entered by hand, it is possible to make the passage in the guide sufficiently small, but the process is more expensive partly on account of the extra help required and partly because the speed 35 must be kept down sufficiently to allow the workman sufficient time to seize the material with the tongs and return it to the next pass.

The present invention is for the purpose of avoiding the above mentioned disadvantages and consists mainly of an arrangement by which the guide is kept open to allow the material to enter and is automatically closed after the material has been gripped by the rolls. By this means the entrance of the 40 material into the guide is greatly facilitated, while a satisfactory guidance is obtained. The guide may be maneuvered either electrically, hydraulically, pneumatically, mechanically or by any suitable combination 45 of the above. The impulse required to make

the closing mechanism function may be obtained in several ways as explained in the following:

The invention makes it possible to use repeaters on both sides of the mill even when an oval section is to enter a square pass and still obtain the same high quality of work as by hand, while reducing the number of helpers required. Since the material can be looped over automatically, the speed of 55 the rolls can be considerably increased with a corresponding increase in the capacity of 60 the mill. In continuous mills it is possible to obtain the same accurate dimensions as in looping mills if stretching is avoided between the stands. 65

The accompanying drawings show the preferred form of an embodiment of the invention, in which drawings

Figure 1 shows an axial section through a guide, the rolls being shown in cross-section, and 70

Fig. 2 is a front elevation of a mill equipped with my improvement.

A pair of work rolls 15 and 16 are illustrated between which is to be passed the bar 75 14 for the purpose of reducing it. The purpose of the invention is to guide the oncoming portion of the bar as it is passing between the rolls.

The guide is represented as comprising 80 two halves denoted by the numerals 1 and 2 which are carried by bell crank levers 32—33 rotatable about a fixed pivot 34. The bell crank levers are connected to links 37 and 38 by means of joints 35 and 36. The links 37 and 38 are connected to a bar 41 through a joint 39. This bar is attached to the core 11 of a magnet which is mounted on 85 the frame of the machine, the magnet being energized in a manner presently to be described for closing the jaws after the bar has commenced to run through the rolls.

The circuit can be closed or broken in the manner illustrated. When the guide is open, 90 the material 14 enters the pass between the rolls 15 and 16 and after the end has passed between the rolls, it comes into contact with a contact arm 18 pivoted at 17. Fixed to the arm 18 and movable therewith is a flexible 95 100

contact arm 19 provided at its outer end with a contact 20. As the contact arm 18 is swung about the pivot 17 the contact 20 connects with another contact 21 thus closing 5 the circuit. The magnet then lifts the core and the guide is closed. When the material has passed through the pass the contact arm 18 falls down, either of its own weight or under the influence of a spring or other 10 suitable means, and the circuit is broken and the guide open.

The speed of the wire in continuous wire 15 rolling mills sometimes exceeds 20 m/sec. As a certain amount of time is required for 15 the device to function and close the guide, the end of the wire will thus have time to run several meters before the guide is closed. On this account it may sometimes be 20 advisable to allow the guide closing arrangement of one stand to be controlled by a releasing mechanism on the previous stand or at any suitable location between the stands. It should, however, be seen to that the rolls 25 grip the wire before the guide is closed.

Having described my invention, I claim 25 and desire to secure by Letters Patent:

1. The combination with a mill provided 30 with rolls, of guides for the material adapted to open and close, and an electro-magnetic device associated with the guides and adapted 35 to close the guides after the material has been gripped by the rolls, and to open the guides after the material has passed from the rolls.

2. The combination with rolls of a rolling 35 mill, of a guide for the material adapted to open and close, an electro-magnet for actuating the guides, and a tripping device in the path of movement of the material passing 40 from the rolls constructed and adapted for closing the circuit of the magnet upon the forward end of the material passing from the rolls, and to open the circuit upon the rear end of the material passing out 45 from the rolls.

3. The combination with a rolling mill, of 50 a guide for the material adapted to open and close and electro-magnet for actuating the guide, a circuit closer for the circuit of the magnet, and a pivoted arm associated with the circuit closer and adapted to lie in the path of movement of the material coming from the rolls.

In testimony whereof I have signed my 55 name.

PER GUNNAR PALMGREN.
